UNITED STATES PATENT OFFICE.

ANDRÉ BECHLER, OF MOUTIER, SWITZERLAND.

DRIVING MECHANISM FOR THE MOVING PARTS OF AUTOMATIC AND SEMI-AUTOMATIC MACHINE-TOOLS.

1,137,180.

Specification of Letters Patent. Patented Apr. 27, 1915.

Application filed December 22, 1914. Serial No. 878,530.

To all whom it may concern:

Be it known that I, ANDRÉ BECHLER, a citizen of the Swiss Republic, and residing at Moutier, Switzerland, have invented cer-

5 tain new and useful Improvements in and Relating to Driving Mechanism for the Moving Parts of Automatic and Semi-Automatic Machine-Tools, of which the following is a specification.

10 It is generally known in connection with automatic and semi-automatic machine tools for the manipulation of wood, metal or the like, to operate the automatically moving machine parts, such as slides, spindles, 15 chucks and the like by means of cams and the like. In order to adapt machines of this type to manipulate blanks of different size and shape it is necessary to have at disposal for each automatically operated member, 20 several interchangeable cams of dissimilar profile in order to be able to vary the stroke of the corresponding machine part. It is quite evident that machines of this class in which several tools are employed, such as 25 for instance in automatic machines, are made relatively too inexpensive on account of the number of the necessary accessories.

My invention has for its object to provide 30 a driving mechanism for the moving parts of automatic and semi-automatic machine tools, in which interchangeable cams are entirely dispensed with.

According to my invention each automatically operated part of the machine is 35 operated, by the intermediary of suitable motion-transmitting members, by means of stops which are arranged adjustably upon a stop drum to which there is imparted on the one hand a straight line reciprocating 40 motion and on the other hand a displacement independent of the reciprocating motion, in such a manner that after each reciprocation of the stop drum another group of stops is brought into the working position.

In the accompanying drawings are shown 45 apparatus constructed in accordance with my invention as applied to an automatic lathe.

50 Figure 1 is a side view of the machine, certain parts being omitted in order to more clearly show the operation of the machine.

Figs. 2 and 3 show corresponding front and rear views, while Fig. 4 shows diagrammatically the driving mechanism for the 55 stop drums.

Cylindrical stop drums *b*, *c*, *d* are keyed upon a shaft *a* which is movable in the axial direction, each of said stop drums carrying a number of sliding pieces *e* distributed 60 upon the whole cylindrical surface of the stop drums and arranged movable in longitudinal grooves. Each slide piece *e* can be displaced in its groove by means of an adjusting screw *e'* and is provided with a 65 number of screwed holes *g* into which are screwed set screws *h* which serve as stops.

Each of the stop drums *b*, *c*, *d* is intended to operate a movable part of the machine. For this purpose a lever *k* is arranged tangential to the stop drum *b*, the fulcrum of said lever being secured to the frame *i*. The free end of this lever is jointed to a link *l* which is again jointed to the lower end of a lever *n* pivoted at *n'* and connected at *m* to a part of the head stock *q*. A striker *p* is secured by means of a nut *o* to the lever *k* so that when the shaft *a* with the stop drums is moved axially, one of the screws *h* strikes against the striker *p* and 80 imparts to the lever *k* a certain angular movement. The movement of the lever *k* is transmitted to the lever *n* and from thence to the head stock *q* which is connected in a suitable manner with the lever *n*. In a similar manner the spindle *s* is moved axially 85 by the stop drum *d*, the stops of which act upon the lever *t*; the latter is mounted rigidly upon the shaft *u* which carries at its other end an arm *v* whose free end is provided with a projection *w* which engages in a circular recess *x* of the driving wheel *y*. The spindle *s* to which the tool, for instance spiral drill, is secured, receives its rotary movement from the wheel *y*, while its to-and-fro movement is imparted to it from the stop drum *d* through the intermediary of 90 levers *t* and *v*.

Fig. 3 shows another part of the mechanism, the object of this mechanism being to impart to the tool *i* the necessary to-and-fro movement from the stop drum *c*. The tool is secured to a slide 95 2 which is moved to-and-fro by means of a

spindle 3. Upon this spindle is rigidly secured a small toothed wheel 4 which engages with a toothed sector 5 which forms the end of one arm of a two armed lever rotatable at 6. The other arm 7 of this lever engages, by means of a projection, in a slot 8 of a vertical slide 9 which is put into motion by means of the stop drum *c* through the levers 10 and 11. The shaft *a* in addition to its axial movement also executes a periodically rotary movement. The drive for this shaft is shown diagrammatically in Fig. 4. A disk 12 which is keyed rigidly upon the shaft *a* engages in a cam groove 13 of a cam drum 14. The latter is rigidly keyed on a shaft 15 and connected with a worm wheel 16 which receives its drive from a worm 17. Upon the shaft *a* there is further mounted a toothed wheel 18 which drives the shaft *a* by means of a key 19, which latter however permits of the axial movement of the shaft *a* independent of the wheel 18. A projection 20 secured upon the shaft 15 engages in the tooth of the wheel 18 on each rotation of the shaft 15 thus rotating said wheel one tooth farther. The drive of the shaft *a* could of course be effected in any other suitable manner.

The method of working the device is as follows:—When the machine is put into motion the shaft 15 and the roller 14 are rotated by means of the worm 17. The cam groove 13 causes the axial movement of the shaft *a* together with the stop drum *b*, *c*, *d* mounted thereon. It is evident that if the stops *h* have been adjusted so that for instance only the striker *p* of the arm *t* is in the path of one of the stops, only the spindle *s* will be actuated upon the axial movement of the shaft *a*, while the head stock *q* and the slide 2 remain at rest. The forward movement of the shaft *a* is effected during the first half rotation of the cam drum 14, while during the second half rotation of the roller the shaft *a* moves back into its original position, the spindle *s* is consequently moved into its original position by the action of a spring 21 which could of course be replaced by a stop mounted on the stop drum *d*, which would come into action upon the return movement of the shaft *a*. When this roller 14 has effected a complete revolution the projection 20 rotates the wheel 18, the shaft *a* and the stop drums. By this means the stops of one of the drums *c* or *b* come into working position so that on the next rotation of the shaft 14 either the slide 2 or the head stock *q* comes into action.

I generally construct the machine in such a manner that the different automatically moved parts are actuated one after the other but two or more of these parts could be operated simultaneously. Any number of movable parts may be operated in the man-

ner described and instead of the stop drums 65 being arranged on cylindrical drums they can be arranged in any other suitable manner.

Having now described my invention, what I claim as new and desire to secure by 70 Letters Patent is:—

1. Driving mechanism for the moving parts of automatic and semi-automatic machine tools, comprising a tool supporting member, a stop supporting member independent thereof, stops mounted on said stop supporting member, means for imparting to said stop-supporting member a straight-line reciprocating motion, and means for imparting to said stop-supporting member a 80 motion, independent of said straight line reciprocating motion, for the purpose of bringing another stop into the working position.

2. Driving mechanism for the moving 85 parts of automatic and semi-automatic machine tools, comprising a stop-supporting member, stops mounted thereon, means for imparting to said stop-supporting member a straight-line reciprocating motion, and means for imparting to said stop-supporting member, a motion independent of said straight-line reciprocating motion for the purpose of bringing another series of stops, 90 into the working position and means for imparting the movement of said stops to the moving parts to be actuated.

3. Driving mechanism for the moving parts of automatic and semi-automatic machine tools, comprising a stop-supporting 100 drum, stops mounted thereon, means for imparting to said stop-supporting member a straight-line reciprocating motion, and means for imparting to said stop-supporting member, a motion independent of said straight-line reciprocating motion for the purpose of bringing another series of stops 105 into the working position and means for imparting the movement of said stops to the moving parts to be actuated, adjusting 110 screws for adjusting the position of the stops on the supporting member, a shaft movable in the axial direction, said stop-supporting drum being rigidly mounted 115 thereon.

4. Driving mechanism for the moving parts of automatic and semi-automatic machine tools, comprising a stop-supporting drum, stops mounted thereon, means for imparting to said stop-supporting member a 120 straight-line reciprocating motion, and means for imparting to said stop-supporting member, a motion independent of said straight-line reciprocating motion for the purpose of bringing another series of stops 125 into the working position and means for imparting the movement of said stops to the moving parts to be actuated, adjusting

screws for adjusting the position of the stops on the supporting member, a shaft movable in the axial direction, a plurality of stop-supporting drums being rigidly mounted thereon, each of said drums being adapted to actuate one of the moving parts to be actuated.

In testimony whereof I have signed my name to this specification in the presence of two subscribing witnesses.
